Osborn M. Miller INVENTOR

BY Edward Thomas
ATTORNEY

UNITED STATES PATENT OFFICE

OSBORN MAITLAND MILLER, OF NEW YORK, N. Y.

PRINT

Application filed July 10, 1928. Serial No. 291,672.

This invention relates to prints and to the production of accurately graded half-tone tints from untinted drawings for conventional representation and is herein illustrated 5 as applied to the production of hypsometric tints on contour maps.

Hitherto hypsometric tints on maps have been obtained by successive printings with different color plates. Such tints as are recommended for the International map of the world require six color plates for land and two more plates for water, besides the three base plates, black, red and blue, for cultural detail. Some of these tint colors are preferably printed both from a light and a heavy plate, with the result that as many as nineteen impressions may be used in printing a single sheet. Thus the process is slow, expensive, and offers many opportunities for spoiling the work, especially from imperfect register of the many successive impressions.

According to the present invention many of these and other difficulties are avoided. According to the present invention the hypsometric tints of the map are shown as evenly toned areas of variously graded half-tones usually printed from a single plate, though, if it is desired, different cultures may be shown in different colors of graded half-tone, such as green for forest, and uncultivated land in sepia, or other conventionalized tints.

To accomplish these results there is first prepared "copy", to use a printer's term, which forms basis from which to work up the desired tints. The "copy" is, however, preferably not altered itself, but the work may be done on a photographic positive or negative on glass or other material, made 40 from it, either directly or indirectly and either by contact printing or in a camera.

This positive or negative is then used as secondary "copy" or worksheet from which the ultimate printing plate is eventually made. To thus make the printing plate a series of incomplete exposures are superposed on a sensitized surface from the above-mentioned copy, and the surface of the latter 50 copy is altered after each exposure so as to

eventually produce the desired effect when the final exposure has been made.

In the case of a hypsometric map the alternation of the worksheet consists in altering the area of the next contour by either 55 painting it over with black or else removing a black surface therefrom. One incomplete exposure is made before the altering of the surface of all the area of the map and leaves a faint developable latent image on 60 the sensitized surface. The second exposure of the sensitized surface causes the surface of the worksheet, where black, to leave the same latent image, while the unaltered unblackened surfaces add to the faint latent 65 image with the result that the parts of the sensitized surface which have twice received the impress of an unblackened surface have a latent image of increased depth. The area of another contour interval is then altered 70 as by blackening and the sensitized surface receives the impress of the map, adding further to the latent image in unblackened parts. The process is thus repeated until the shades of the map are complete in the latent image 75 of the sensitized surface. Then the image is developed in the usual way. From this image showing the graded tints in positive values the printing plate is made in any desired or usual manner for printing the half tones 80 in printing ink.

The foregoing description outlines one procedure in which the desired tints are obtained by rendering non-actinic successive area of the secondary copy as by blackening to produce by photography a positive copy showing the required hypsometric tints, but as will hereinafter appear, the desired successive tints may also be obtained by a reversal of the procedure, viz. by scraping off the areas 85 successively from a "copy" negative, with intervening incomplete exposures to successively build up a latent image of the parts not scraped away, increasing with the number of incomplete exposures.

Other features and advantages will hereinafter appear.

Figure 1 is a sectional side view, largely diagrammatic, of an apparatus used in carrying out one form of my process.

Figure 2 is a schematic diagram summarizing one procedure for producing the desired maps, in which a positive print of the required tints is built up by photography from a positive "copy."

Figure 3 is a schematic diagram summarizing an alternative procedure, in which a half tone negative of the required tints is built up by photography from a negative "copy."

10 Figure 4 is a schematic diagram summarizing another alternative procedure in which a half tone negative of the required tints is built up by photography from a positive "copy."

15 Figure 5 is a schematic diagram summarizing another alternative procedure resembling the procedure of Figure 4 but especially adapted for commercial practice.

Method I. According to one form of the 20 present invention illustrated in Figure 2, there is made from the draftsman's finished "copy" containing the conventional lines and, in a map, contour lines, one negative as a starting point for the plate of uniformly 25 graded tints and another identical negative as a starting point for the line plate. Both of these negatives are made, as usual, with the image "reversed," that is with an image which is the reflection of the original, so that 30 left hand is right hand and right hand, left hand.

From the negative for making the plate of uniformly graded tints there is made a glass positive by contact printing. This positive is 35 "unreversed" and is an exact image or reproduction of the "copy" used as a starting point.

From the positive which serves as secondary "copy" there is made a series of incomplete exposures by contact printing on the sensitized surface of an opal white glass plate. The first of these incomplete exposures produces a latent image which will ultimately show as the lightest hypsometric tint on the finished map. The area of the 40 secondary "copy" positive which is to show as the lightest of the hypsometric tints is then rendered non-actinic or blackened, and a second incomplete exposure made on the opal glass plate so that the area, except that representing the non-actinic part of the secondary "copy," now receives an addition to its latent image until the parts representing the unblackened area carry a latent image 45 representing next to the lightest hypsometric tint. Thus now the latent image on the opal glass plate represents the two lightest successive hypsometric tints.

The area of the secondary "copy" positive 50 which is to show as the second lightest of the hypsometric tint is then rendered non-actinic so that the areas which will eventually show in the finished map as the two lightest hypsometric tints are now black. Then a third incomplete exposure is made on the opal glass

plate so that the area, except that representing the non-actinic areas of the second "copy," now receives an addition to its latent image until the parts representing the unaltered area carry a latent image representing the third hypsometric tint. Thus now the latent image on the opal glass plate represents the three lightest successive hypsometric tints.

70 The altering of successive areas to render them non-actinic and the printing of incomplete images are then continued until all the desired tints are represented in the latent image, after which the image is developed and fixed on the opal glass plate.

The opal glass print, a reversed print 75 shows the conventional black lines of the finished map or diagram as white lines against the tinted background so that when the line plate impression is made on the finished print there will be no overlapping of lines and tinted areas. Moreover, in a map, the tops of the hills may be light and valleys dark, instead of the contrary which is now customary. Thus the dark valleys now need 80 not mask the cultural line details.

85 This glass print is now shade or tint copy. From this tint copy is made in an ordinary half tone camera a negative of the required tints, which will be an unreversed negative. 90 From this last-named negative is made by contact printing the half-tone positive plate from which the tints are printed in a printing press on the "proof" of the map or diagram.

95 For this particular procedure for printing the lines of the map or diagram the reversed negative made as a starting point for the line printing plate is "turned," or stripped, reversed and remounted, and then from it is made in any usual or desired manner, as by contact printing, the positive line printing plate from which the conventional black or other lines of the map are printed in a printing press.

100 The finished print shows tints as evenly shaded half tone shades with the lines printed in areas left blank imprinting the half tone tints. Usually, at one side or end, the map or diagram shows a scale of the tints 105 printed with adjacent numerical values.

110 Method II. According to one procedure for carrying out an alternative method, shown schematically in Figure 3, two identical reversed negatives are made, one as a starting point for the graded tints plate, and the other for line printing plate.

115 The negative from which is eventually obtained the hypsometric tints is then used as "secondary copy." From it is made a series 120 of incomplete exposures on a sensitized transparent surface behind a half-tone screen in an ordinary half-tone process camera, the image on the secondary copy being successively cut away step by step as exposures pro- 125

ceed. An apparatus for use in this procedure is shown in Figure 1.

The half tone camera 1, with a shutter 2, a lens 3, variable diaphragm 4, bellows 5, and screen 6, is firmly mounted on the usual base 7 so that it can be focussed. Behind the screen 6 is the sensitive plate 8 which will form the half-tone negative. The camera is focussed on the "secondary copy" 9 which is mounted in a swinging frame 10, carefully built to be swung up repeatedly to focussing position and accurately adjusted there by a stop and lock 11.

Before any exposures are made the portions of the image which will be white on the final map are cut away, or scraped clear of silver. An incomplete exposure is then made with a white or illuminated background behind the secondary copy, so that a latent image is formed. This image must eventually become the black of the image on the plate in the camera.

After the first incomplete exposure the secondary copy 9 is swung down in its frame 10 so as to rest on the base 7. Then the operator cuts away the parts of the image in the secondary copy which are to appear as the lightest tint in the finished map or diagram. The secondary copy is then swung up and a second incomplete exposure made, sufficient to make a new latent image on the plate in the camera of the area in which it will show the shade next lighter than black and to add to the first latent image. Then the secondary copy is again swung down the operator cuts away the parts of the image in the secondary copy which are to appear as next to the lightest tint in the finished map or diagram. The secondary copy is then swung up, and a third incomplete exposure made, to impress a new latent image on the plate in the camera of the area in which it will show the shade two shades lighter than black, and to add to the previous latent images.

This process is continued until the operator is ready to remove the last of the silver deposit on the secondary copy. The exposure of that completes the last hypsometric tint and the plate in the camera is then developed resulting in a half tone negative. From this negative is made the usual half-tone positive printing plate, and from the latter the graded tints of the map or diagram are printed.

The plate for printing the lines of the drawing is made from the second identical negative mentioned above, precisely as in the first method and used for printing in the same way.

Method III. According to one procedure of carrying out a third method, shown schematically in Figure 4, the "finished copy", coming from the draughtsman is photographed, and the resulting reversed

negative turned, so that it is, in effect, unversed.

From this turned negative is made a faint or blue reversed print on opal white glass to serve as secondary copy or worksheet, so that the lines show just enough to enable the operator to follow the contour lines in rendering areas non-actinic as will hereinafter appear.

The secondary copy is then made non-actinic at the areas which are to appear black or as the darkest tint in the finished map. From this secondary copy is then made an incomplete exposure through the half tone screen on a sensitized plate in the camera. Then the operator renders non-actinic the area which is to be the next shade lighter in the finished print, makes a further incomplete exposure of that on the plate in the camera. The operator then renders non-actinic the area which is to be one further shade lighter in the finished print, makes an incomplete exposure of that in the camera, and continues the operations until the last area on the secondary copy is ready to be exposed, exposes that, and develops the sensitized plate with the successive incomplete exposures in its latent images, resulting as in Method II in a half tone negative of the required tints.

From this developed and fixed negative is prepared in the usual way the half-tone printing plate for printing the graded tints.

The plate for printing the lines on the map is made directly from the same turned negative which was used for printing the faint-lined secondary copy.

Thus the half tone tint printing plate and the line printing plate should register exactly as both have been made from the same turned negative without any further turning.

Method IV. According to a fourth method shown schematically in Figure 5, two secondary copies or worksheets are prepared, one for the half tone tint plate and one for the line plate.

According to one procedure for carrying out this method there are two or more identical contact reversed blue prints on opal white glass plates. One of these blue prints is used as the tints plate secondary copy. First the area which will eventually appear as black in the finished map or diagram is altered or rendered non-actinic on the secondary copy, then there is made an incomplete exposure on a sensitized plate in the camera behind the screen of the partly altered copy. Then the operator renders non-actinic the area on the secondary copy which will appear in the map as the next lighter shade, makes an incomplete exposure of this. This is followed by successive incomplete exposures, until the final area, which is to appear as white, has been impressed upon the plate as a latent image by an incomplete exposure. Then the plate when developed and fixed

is an unreversed half tone negative and is used in the usual way for preparing the half tone positive plate for printing the tints.

The other reversed contact blue print on 5 secondary copy for making the line plate shows on a blue ground the white lines of the original copy. These lines are inked in by a draftsman in waterproof ink, and then, if necessary, the blue is bleached. From this 10 inked-in plate is made the line printing plate.

It will be noted that the process just described provides guide lines both for inking in the hypsometric tints and for inking in the lines of the plate for line printing the 15 map, but that the blue print lines will not ordinarily show on the plates made from the blue prints.

The unreversed half-tone negative may be used in preparing as many half-tone positive 20 printing plates as are needed for printing the various desired colors on the print. They may be used, for example, to print on a map colors indicating different cultures, such as forested and cultivated land, in different 25 colors but in exactly corresponding hypsometric tints. To make a plate for printing only part of the print in a given color, the area of the printing plate which should not print may be "routed" or cut away, and the 30 plate which prints another color is "routed" or cut away at the area where the first plate prints, and so for several plates. Line printing plates may be cut away in similar fashion to print any desired areas in any selected 35 colors.

In this fourth method of producing half-tone and line printing plates there is no turning of a negative, thus the resulting distortion is absent, and the reproductions may be 40 absolutely accurate.

In following the foregoing descriptions it must be remembered that the latent image formed is not directly proportional to the time of exposure or to the amount of light 45 falling on a sensitized surface, so, to make uniformly graded tints from any given emulsion, the time of exposure or the diaphragm, or both must be varied according to the characteristics of the emulsion and the time of 50 development. Moreover the emulsions may be carried on any suitable backing. Glass has been named because it is usually most satisfactory, since it does not swell or shrink, but paper positives or celluloid negatives may 55 be used for rough work.

Having thus described certain embodiments of my invention, what I claim is:

1. The process of making accurately graded half tone tints on a print which consists in 60 making a photographic copy of the drawing, successively altering the surface of successive areas on said copy, successively photographing on a single plate the copy after each alteration to build up and add to a latent image of the successive alterations, and

preparing from the developed latent images a half-tone printing plate.

2. The process of making plates for a hypsometric map which consists in making a photographic copy of the drawn map, successively altering the surface of successive areas on the said copy, photographing on a single plate the copy after each alteration to build up and add to a latent image of the successive alterations, preparing a half tone printing plate from the developed half tone negative, and making a line printing plate from another copy of the original drawing.

3. The process of making plates for printing in two or more colors evenly graded half tones and line printing therewith, which consists in making a secondary photographic worksheet, successively altering the surface of successive areas of the secondary worksheet for producing the plate used for half tone printing, photographing on a single plate after each alteration of it to build up and add to a latent image of the successive alterations, preparing for each color a half-tone printing plate from the developed latent images, and making a line printing plate from another secondary worksheet.

4. The process of making plates for printing in two or more colors evenly graded half tones and line printing in two or more colors which consists in making a secondary photographic work sheet, successively altering the successive areas of the secondary work sheet for producing the plates used for half tone printing, photographing on a single plate the work sheet after each alteration of it to build up and add to a latent image of the successive alterations, preparing for each color a half tone printing plate from the developed latent images, drawing on a secondary work sheet for the line printing plate the lines to be printed by the color line plates, and preparing by photographic processes a line printing plate for each color from the secondary work sheet.

5. A print having half-tone tints of accurately graded density, separately printed conventional solid line representations, and a scale printed on the sheet having numerical values printed adjacent specimen tint areas.

6. A print having both solid line representations and evenly graded half tone representations, the solid lines being printed independently in spaces substantially empty of half tone printing.

7. A print having evenly graded half tone tints of a single color, and solid lines printed independently of the half tone colors.

8. A hypsometric map having altitudes printed in evenly graded hypsometric half tone tints of one color for one conventional representation, other evenly graded half tone tints of another color for another con-

ventional representation, and solid lines printed independently of the colors.

9. A printed map showing by even half tones of the same color but of different densities proportional representations of the same phenomena, as differences of elevation or density of population, and lines of solid color printed in spaces substantially free of half tone densities and separating the different densities.

10. A printed map showing by even half tones of different densities and different colors both distribution of different phenomena and proportional distribution of the same phenomena such as altitude and vegetation.

11. The process of reproducing line drawings so that the printed reproductions show in addition to the lines, half tone units of various uniform densities over limited areas, which consists in photographing on a plate the line drawing, successively obliterating successive areas on said drawing, successively photographing on the same plate the drawing after each obliteration to build up a latent image having successive densities determined by the successive obliterations, developing the latent images, and printing from a half tone printing plate embodying those latent images to obtain the final reproduction.

OSBORN MAITLAND MILLER.
